UNITED STATES PATENT OFFICE.

IRVING L. KEITH, OF HAVERHILL, MASSACHUSETTS.

SQUEAK-PREVENTER FOR SHOES.

1,075,039.

Specification of Letters Patent.

Patented Oct. 7, 1913.

Application filed May 7, 1913. Serial No. 766,101.

To all whom it may concern:

Be it known that I, IRVING L. KEITH, a citizen of the United States, residing at Haverhill, in the county of Essex and State 5 of Massachusetts, have invented an Improvement in Squeak-Preventers for Shoes, of which the following is a specification.

It is a well-known fact that squeaking of shoes is usually caused by the rubbing together of two portions of the shoe bottom or sole when bent, and, to prevent this, it has been common practice to place various substances, such as tarred felt, powdered chalk or talc between the parts which are likely to 10 rub together. While a powder, such as powdered talc, is perfectly effective in preventing squeaking, when properly applied, as a practical matter, it is extremely difficult, in the ordinary process of shoe manufacture, 15 to place it between the parts in the position desired, and in such a manner as to perform its intended function.

It is customary, in the manufacture of many shoes, to reinforce the outer sole by 20 cementing a tap to the inner side of the sole, before the sole is attached to the upper, the usual method being to apply a coating of cement over the entire surface of the sole fore-part, then place the tap thereon and 25 press them firmly together until the cement has set. However securely the tap and sole may be held together by cement, when the shoe is worn, the constant strain due to the bending of the sole usually causes the cement 30 to give way, so that the tap and sole will rub on each other, causing the shoe to squeak. It is very difficult, and practically useless, when employing this process of cementing 35 taps to soles, to place a powder between the sole and tap at this time, for various reasons.

If a suitable quantity of the powder were placed on either the sole or tap it would be liable to spread over the surface thereof and prevent them from adhering one to the 40 other, and when the freshly cemented soles were placed in a stack and compressed, they would be liable to slip out of position. Moreover, the fresh cement would cause the powder to adhere to the cemented piece, so that 45 the powder would be prevented from later working into the spaces where the parts rub on each other, and, in order that the powder may be effective in preventing squeaking, it must be free to work into any space which 50 may be formed by the separation of the parts. It is not practical to use tarred felt

between a tap and sole for various reasons, principally because it is so thick that a piece in the middle portion of the sole would prevent the tap and sole from adhering at 60 their edges when pressed together. It is also expensive and inconvenient to use in other relations.

The object of my invention is to provide 65 a means, whereby a powder, such as powdered talc, may be effectively employed between the different parts of the shoe to prevent squeaking thereof, and may be conveniently placed between a tap and an outer sole, before they are cemented together, without 70 materially increasing the cost of manufacture, or preventing the complete closing of the joint between the tap and sole, at the edges, and without being affected by the fresh cement which is employed, when it is 75 inserted, so that it will thereafter be free to become distributed over the entire surface portions which may rub on each other. I accomplish this object by providing a suitable 80 quantity of the powder, which is commonly used to prevent squeaking, and placing the same in an envelop of very thin, easily frangible material, as tissue paper, or gauze, the packet thus formed being placed, at the time the shoe is being made, between 85 the parts which would rub together, so that the powder will be protected by the envelop from the cement, which may be used to cause these parts to adhere, and when the shoe is 90 worn, or the sole is bent, the envelop will break or be disrupted and the powder will work out or sift out into the spaces between the parts which would otherwise rub on each other.

Various embodiments of my invention are 95 possible, some of which are shown in the accompanying drawing, in which:—

Figure 1 is a plan view of a sole illustrating an application of my invention. Fig. 2 is a similar view showing a slight modification. Fig. 3 is an enlarged detail sectional view of a sole and tap provided with my invention. Fig. 4 is a perspective view of a form of packet which I preferably employ. Fig. 5 is a plan view illustrating the manner 105 in which the packet may be broken open.

According to my invention I provide an envelop *a*, which is preferably of a thin tissue paper, and which is, to an extent, impervious to cement, and place therein a 110 quantity of powdered talc, chalk or similar material *b*.

In the process of cementing a tap to an outer sole, for example, a coating of cement is usually applied to the outer sole *c* throughout its entire fore-part, and then, to incorporate my invention, the envelop *a* containing the powder, which has preferably been sealed therein, so that the powder will not be spilled, is placed in the middle of the fore-part, or approximately opposite the ball of the foot, which is the point at which the sole is bent to the greatest extent and is, therefore, the point at which squeaking is most likely to occur. The packet is of materially less size than the size of the sole, so that there will be a wide space between the edges of the packet and the edge of the sole. The tap will then be placed in position on the sole and the parts will be pressed together, so that the surfaces about the packet will be caused to adhere. As the packet is very thin and flat, the amount of powder which it is necessary to use being very small, it will not interfere with the pressing of the edge portion of the sole and tap together. That is, the package is so thin that its pressure is not in any degree noticeable and its use does not in any way detract from the value of the shoe. After the tap and sole have been sewed to the upper and the shoe is worn, so that the sole will be bent, the envelop will immediately be ruptured, as indicated in Fig. 5, permitting the powder to work out between the tap and sole and into any space where they may happen to become separated, and in this way it will prevent any squeaking when the sole is bent. While the use of this frangible powder packet, in the particular relation above referred to, is particularly desirable, it may also be used to advantage in other portions of the shoe, where there is any liability that the parts will rub together so as to squeak;—for example, it may be desirable to use the same in the

shank of the shoe, as indicated by the packet *c* in Fig. 2, or between an inner sole and outer sole, as well as between a tap and outer sole.

The particular form of envelop is not essential, as it may be made in various forms, and of various different materials, without departing from the spirit and scope of my invention, *i. e.*, may be made in triangular, or oblong form, as shown, or any other form which is best adapted for the particular part of the shoe in which it is to be placed.

I claim:—

1. In combination with two portions of a shoe having engaging surfaces, a frangible envelop disposed between said surfaces and having a powder therein adapted to prevent rubbing contact of said surfaces when liberated from the envelop, substantially as described.

2. In combination with two sole-portions of a shoe arranged one directly on the other, a flat, frangible envelop, of relatively small area to that of said sole portions, arranged therebetween in the middle portion thereof, said envelop having a suitable quantity of squeak-preventing powder therein adapted to be liberated from the envelop when ruptured, substantially as described.

3. In combination with two superimposed, contacting sole-portions of a shoe, an envelop disposed between said portions, having a squeak-preventing powder therein, and adapted to permit the powder to escape therefrom when said sole portions are bent, substantially as described.

In testimony whereof, I have signed my name to this specification, in the presence of two subscribing witnesses.

IRVING L. KEITH.
